UNITED STATES PATENT OFFICE

2,639,667

CURVED PLATEN PRINTING PRESS

Joseph F. Jirousek, Cleveland, Ohio, assignor to
 The Chandler & Price Company, Cleveland,
 Ohio, a corporation of Ohio

Application June 5, 1947, Serial No. 752,732

4 Claims. (Cl. 101—297)

1

This invention relates, as indicated, to platen printing presses and more particularly to such presses in which a rolling contact is obtained between the sheet on the platen and the form. It has long been recognized (see U. S. Patent No. 1,034,083 to Clark, dated July 30, 1912) that there are certain advantages in cylinder presses over the Gordon or platen type press including the fact that the sheet to be printed contacts the impression cylinder progressively with relatively little area in contact, whereas in the conventional Gordon press the entire sheet carried on the platen receives the full impression from the form at one time. This calls for the application of a great deal of force and requires great strength and rigidity in the supporting elements of the press.

In my application Serial No. 672,631 "Platen Printing Presses," filed May 27, 1946, now U. S. Patent No. 2,602,396, I describe and claim a platen printing press affording rolling contact of form and platen in a manner to effect a firm and consistent reproducible impression. The present invention relates to certain improvements in the operating mechanism of this type of press.

It is most important that the means employed to move the platen into and out of impression position be firm and positive in their action and also that such means should not obstruct the platen and interfere with the feeding of sheets to and the delivery of sheets from the same.

It is, therefore, a primary object of my invention to provide improved operating mechanism which will thus permit feeding and delivery of the sheets from either the forward edge or from the sides of the platen. Such mechanism is particularly arranged to facilitate so-called cross-feeding and delivery of the sheets wherein the sheets are fed from one side of the platen and delivered to the other side.

Other objects and advantages will become apparent as the following description proceeds.

To the accomplishment of the foregoing and related ends, said invention, then, comprises the features hereinafter fully described and particularly pointed out in the claims, the following description and the annexed drawings setting forth in detail certain illustrative embodiments of the invention, these being indicative, however, of but a few of the various ways in which the principle of the invention may be employed.

In said annexed drawings—

Fig. 1 is a front elevational view of the upper portion of a platen printing press constructed in accordance with my invention; and

2

Fig. 2 is a side elevational view of such portion of such press.

Referring now more particularly to the drawings, the main frame 1 of the press supports the form bed 2 in which the usual chase and form (not shown) are adapted to be secured by the usual locking mechanism 3. The frame is recessed at each side at 4 to permit the lower inking rollers 5 and 6 to move inwardly after their downward passage across the form whereby the upper inking roller 7 is enabled completely to traverse such form. Tracks 8 are provided for such rollers leading from a conventional fountain and distributing disk (not shown).

15 Mounted on said main frame to each side of said form bed 2 are racks 9 extending downwardly from said form bed except where interrupted by recess 4. A platen 10 having a convexly curved face adapted to engage in rolling contact a form carried by said form bed is provided with curved racks 11 along each side and extending downwardly therefrom. Said racks 11 on said platen are adapted to mesh with racks 9 on the main frame of the press in cooperative engagement whereby a precise positioning of the platen relative to the form bed is obtained and preserved. The downwardly extending portion 12 of the platen 10 is more sharply curved than the sheet supporting face thereof and the corresponding portions of racks 11 are likewise more sharply curved than in their upper portions. It will be seen, therefore, that when the platen 10 is rocked to a closed position, as shown in dot-and-dash lines in Fig. 2, the teeth of racks 9 and 11 will progressively mesh, recess 4 being bridged without difficulty, until rolling contact has been made with the entire face of the form. Because of the increased arcuity of the lower portions of racks 11, it will likewise be seen, as 30 illustrated in solid line in Fig. 2, that the platen in open position may be caused to assume a substantially horizontal position thereby greatly facilitating the feeding and delivery operations.

To operate the press, oscillating the platen between solid line and dash line positions of Fig. 2, the following means are provided:

A cam 13 having a large eccentric lobe is keyed to shaft 14 journalled in the main frame of the press. Two arms 15 and 16 carrying cam roller 17 therebetween are keyed to rocker shaft 18 likewise journalled in such main frame. Roller 17 is adapted to engage said cam 13 whereby rocker arms 19 and 20 also keyed to shaft 18 are adapted to be oscillated between solid and 55 dash line positions, as shown in Fig. 2. The

upper ends 21 and 22 respectively of such rocker arms are pivotally connected to the upper portion of the platen 10.

The lower portion 12 of such platen is provided at either side with cam followers in the form of rollers 23 and 24 adapted to travel along cam-ways 25 in side brackets 26 and 27 mounted on the main frame 1. These cam-ways are designed properly to control the movement of the lower end of the platen as the same is rocked into and out of impression position through the action of rocker arms 19 and 20.

In order to obtain the requisite pressure during the impression, means are provided limiting outward movement of lower portion 12 of the platen. Such means comprise lever arms 28 and 29 pivotally mounted in the respective sides of main frame 1 and pivotally connected with the lower portion 12 of the platen by means of links 30 and 31 respectively. Cam rollers 32 and 33 carried by said respective lever arms are adapted to engage cams 34 and 35 respectively, keyed to shaft 14. Such cams are shaped and positioned relative to cam 13 to permit movement of rollers 23 and 24 along cam tracks 25 in synchronism with the rocking of the platen by arms 19 and 20. At the same time, such cams 34 and 35 acting on such lever and link means serve to limit such outward movement of the lower portion of the platen to ensure firm rolling engagement of such platen with the form.

Any conventional means may be employed for driving shaft 14 and thereby operating the press, such means forming no part of this invention. Likewise, throw-off means may be provided similar to that discussed in Johnson Patent No. 2,357,116, dated August 29, 1944, with shaft 14 journaled in an eccentric mount, by angular adjustment of which the platen may be prevented from coming into impression engagement with the form.

To avoid the possibility of a double impression such throw-off means may, of course, be caused to operate automatically as the press is opened after each impression, in the manner generally described in my co-pending application Serial No. 672,631.

It will be seen that I have provided operating mechanism for a rolling contact platen press which is positive and efficient in its action but which may be arranged so as entirely to avoid interference with the feeding of sheets to and the delivery of sheets from the platen. Of course, if desired, the positions of the platen and the form bed may be reversed and the form bed or both form bed and platen provided with a curved surface for rolling contact, although a preferred form is illustrated and described herein. Likewise, it is possible to provide the curved platen with substantially straight rack means and to curve the rack means on the main frame to obtain the desired movement.

Other modes of applying the principle of the invention may be employed, change being made as regards the details described, provided the features stated in any of the following claims, or the equivalent of such, be employed.

I therefore particularly point out and distinctly claim as my invention:

1. In a platen printing press of the character described, a main frame, a form-bed carried by said frame, a platen having a convexly curved surface adapted to make rolling contact with a form in said form-bed when oscillated into impression position, rack means on said frame to

each side of said form-bed and extending below the impression portion of said form-bed, a convexly curved downwardly extending portion on said platen, rack means on said platen to each side of the impression surface of said platen and continuing along said downwardly extending portion below such impression surface, said rack means on said platen meshing with said rack means on said frame to position said platen relative to said form-bed, a shaft rotatably journaled in said frame on an axis parallel to said form-bed, a cam mounted on said shaft for rotation therewith, a rocker arm mounted on said frame and pivotally connected to the upper portion of said platen, said cam being adapted to rock said arm to rock said platen into and out of impression position, a cam track on said frame, a cam follower on the lower portion of said platen adapted to travel along said cam track, a lever arm pivotally mounted on said frame and pivotally connected to the lower portion of said platen, and cam means operative to limit movement of said lever arm and thereby movement of said cam follower along said cam track in synchronism with the rocking of said rocker arm.

2. In a platen printing press of the character described, a platen convexly curved and mounted to make rolling contact with a form in the form-bed of such press, a main frame, a curved rocker arm pivotally mounted on said frame at a point lower than any operative position of said platen and pivotally connected to the upper portion of said platen, such curve and position of pivotal mounting of said arm being selected to maintain said arm behind the line of the face of said platen in all positions of the latter, whereby such face is not obstructed and feed and delivery of sheets laterally to said platen is facilitated, cam means operative to rock said arm to rock said platen into and out of impression position, a cam track on said frame, a cam follower on the lower portion of said platen adapted to travel along said cam track as said platen is rocked, a lever arm pivotally mounted on said frame, link means pivotally connecting said lever arm to the lower portion of said platen, and cam means operative to limit movement of said lever arm and thereby movement of said cam follower along said cam track in synchronism with the rocking of said rocker arm.

3. In a platen printing press of the character described, a convexly curved platen mounted to make rolling contact with a form in the form-bed of such press, means mounted on the bed of such press, pivotally engaging the upper portion of said platen operative to rock said platen into and out of impression position, said platen rocking means being located below said platen in open position of said platen and thus engaging said platen from below the latter to avoid obstructing lateral access thereto, whereby feed and delivery of sheets to said platen may be facilitated, and means on the bed of such press engaging the lower portion of said platen adapted to control in and out movement of the lower portion of said platen as said platen is rocked, said last-named means comprising a guideway engaging the lower portion of said platen and power driven means operative to control the position of such lower portion of said platen along said guideway.

4. In a platen printing press of the character described, a curved platen mounted to make rolling contact with a form in the form-bed of such press, a rocker arm pivotally mounted on the bed of such press and pivotally connected to the

upper portion of said platen, guide means on such bed engaging the lower portion of said platen in all operative positions of the latter, cam means operative to rock said rocker arm to roll said platen across such form, and means on such bed connected with the lower portion of said platen operative to control the position of the latter along said guide means in timed relation to such movement of said rocker arm.

10
